CLAIM

The ornamental design for a parasol, as shown and described.

DESCRIPTION

FIG. 1 is a bottom, rear, right side perspective view of a parasol, showing my new design;

FIG. 2 is a top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a contracted statuses view of a parasol;

FIG. 10 is an enlarged view of a portion labelled 10 in FIG. 1;

FIG. 11 is an enlarged view of a portion labelled 11 in FIG. 1;

FIG. 12 is an enlarged view of a portion labelled 12 in FIG. 3; and,

FIG. 13 is an enlarged view of a portion labelled 13 in FIG. 5.

The broken lines in the drawings depict portions of the parasol that form no part of the claimed design.

1 Claim, 13 Drawing Sheets
